UNITED STATES PATENT OFFICE.

ISAAC E. PALMER, OF MIDDLETOWN, CONNECTICUT.

PROCESS OF CONDITIONING TEXTILE MATERIAL.

1,008,613.

Specification of Letters Patent. Patented Nov. 14, 1911.

No Drawing.

Application filed June 17, 1909. Serial No. 502,817.

To all whom it may concern:

Be it known that I, ISAAC E. PALMER, a citizen of the United States, residing at Middletown, in the county of Middlesex and 5 State of Connecticut, have invented an Improvement in Processes of Conditioning Textile Material, of which the following description, in connection with the accompanying drawings, is a specification, like letters 10 on the drawings representing like parts.

This invention relates to processes for conditioning textile material in narrow band like condition, and more particularly relates to the treatment of warp for subsequent use as warp or filling.

The textile material in the conditioning process herein set forth is treated by a liquor, which is preferably a dyeing liquor.

Heretofore a mass or chain of warp has 20 been prepared for passage through and treatment in a dyeing vat by wrapping the mass or chain spirally with yarn or thread in order to preserve the integrity of the mass. This procedure has involved the use 25 of special mechanism for wrapping and unwrapping the yarn or thread from about the mass of warp, as well as involving much time in the preparation of the warp.

By my process the textile material which 30 is preferably chain warp is twisted while in a chain or band upon itself or axially of the mass and in this condition is passed through the treating liquor. The chain warp may be of the usual or any suitable length. It is 35 evident that the textile material may be twisted by the apparatus from which it is delivered into the vat or receptacles containing the treating liquor, substantially as disclosed in my co-pending application No. 40 452,134, Sept. 8, 1908, or it may be twisted independently of such apparatus or mechanism, or the warp may be twisted during and as a part of the warping process. It may be twisted either mechanically or manually. The material is preferably uniformly 45 twisted, but only sufficiently to keep the threads collected, as, for example, a single twist to a yarn. I am aware that it has been the practice to braid two, three or more

strands of yarn together and to color them 50 while braided, in order to produce cloudy or Dresden-like color effects in the yarn. The purpose of my invention is diametrically opposed to this, inasmuch as it is of the utmost importance that the warp yarn 55 be evenly and uniformly treated. To this end, the warp yarn is twisted at as infrequent intervals as is possible while maintaining the individual warps collected together. Any suitable number of warp ends 60 may be united into the mass that is twisted and treated, as for example a very few or five hundred or more. By twisting the warp as described the ends are kept from straggling or becoming misplaced. Preferably 65 the warp thus twisted and subjected to a treating liquor, such as a dyeing liquor is used for warp threads. After the warp or other textile material has been passed through the treating liquor, it is untwisted 70 in any suitable manner.

Having thus described one manner of practicing my invention I desire it to be understood that although specific terms are employed, they are used in a generic and 75 descriptive sense and not for purposes of limitation, the scope of the invention being set forth in the following claims.

1. The process of conditioning spun warp consisting in twisting a chain of spun warp 80 composed of a series of spun warp strands, along the longitudinal axis of said chain, at infrequent intervals, thereby merely to hold said warps collected, in subjecting said twisted chain to the uniform action of a 85 treating liquor, and in finally untwisting said uniformly treated, twisted warp chain.

2. The process of dyeing spun warp yarn consisting in twisting a warp chain composed of a series of spun warp strands, 90 along the longitudinal axis of said chain at infrequent intervals, thereby merely to hold said warp collected, in subjecting said twisted chain to the uniform action of a treating liquor, and in finally untwisting said uniformly dyed, spun warp chain.

3. The process of conditioning spun warp consisting in twisting a chain of spun warp

composed of a series of spun warp threads, at substantially one yard intervals, along the longitudinal axis of said chain, subjecting said loosely twisted chain to the uniform action of a dyeing liquor, and in finally un-twisting said uniformly treated, twisted warp chain.

In testimony whereof, I have signed my name to this specification, in the presence of two subscribing witnesses.

ISAAC E. PALMER.

Witnesses:

FRED. E. FOWLER,
REUBEN M. BURR.
